TOY FOR A NEW GAME

Victor L. Carballal, Miramar, Mariana, Cuba

Application May 29, 1940, Serial No. 337,945
In Cuba March 4, 1940

3 Claims. (Cl. 273—96)

This invention relates to a hand toy for a new game which may be played by all kind of people, young or adult, male or female, requiring only practice and ability of the player; its construction being very simple and economical, and therefore it may be generally used in view of its low cost.

The toy consists of a small and light racket similar to those at present used for table ball games, and which comprises a handle and a main body provided with two holes centrally arranged in the same longitudinal alinement and separated from one another, and a basket secured to one of the faces of the main body covering both holes and adapted to receive a ball introduced in one of the holes and thrusting out the same by impulse of the hand through the opposite hole in such manner as to receive same back through the first hole for being thrust out again through the opposite hole, and so on.

In the accompanying drawing, which illustrates a preferred form of the device:

Fig. 1 is a plan upper view of the racket.

Fig. 2 is a side view of the racket with the basket secured thereto.

Fig. 3 is a sectional view on line 3—3 of Fig. 1, indicating the action of the ball.

Fig. 4 is a perspective view of basket separated from the racket.

Fig. 5 is an upper perspective view of the racket with the basket attached thereto.

As illustrated in the drawing, the toy comprises a flat racket having a handle 1 and a main body 2, at the center of which and in longitudinal alinement and spaced apart, are provided the hole 3, which constitutes the inlet for a ball and the hole 4, which constitutes the outlet of the same after passing through the basket 5.

As it will be observed the hole 3 is of larger diameter than the hole 4 with the obvious object that the ball may have ample space for falling into the basket, such ample space not being required for the outlet hole 4.

The basket 5 is provided with a flange 6 provided with eyes for nailing or screwing same to the bottom of the racket, though it is obvious

that the attachment may be effected in any other manner, or even the basket may be made integral with the racket.

The basket is in the form of a channel conforming to the shape of the ball for guiding the movement of the same, and is attached to the bottom of the racket in such a manner that the edge thereof around the holes may not interfere the free action of the ball.

10 While in the drawing is illustrated a preferred form of racket, it is obvious that any other form may be used; and likewise, instead of the two longitudinal alined holes, similarly arranged transverse holes may be provided, in which case a cross channeled basket may be used.

As illustrated in the drawing, in order to play this game, the ball is introduced through hole 3 falling in the basket, and by an impulse of the hand, forward and upwards, the ball is thrust out through hole 4 and owing to the same movement of the hand falls back through hole 3 and so on in accordance with the ability of the player. The impulsing action should always be forwards so that the ball may move in the direction opposite to the hands of a clock and the movement of the racket should also be forward so as to catch the ball when descending.

What I claim is:

1. A toy or the like comprising a racket including a flattened main body having a substantially oval shape and a handle continuing therefrom, said body having a pair of spaced apertures therein, and a basket in the form of a rounded channel shaped member for connection 30 to the under surface of the body and establishing communication between the apertures for receiving and guiding a ball as it passes from one aperture to the other.

2. A toy or the like as claimed in claim 1, in which the aperture adjacent the racket handle is of a larger diameter than the other aperture.

3. A toy or the like as claimed in claim 1, in which the cross sectional shape of the channel member conforms to the remote outer edge portions of the apertures.

VICTOR L. CARBALLAL.
